J. MILLER,

Oil Still

No. 77,070.

Patented April 21, 1868.

JAMES MILLER, OF ALLEGHENY CITY, PENNSYLVANIA.

Letters Patent No. 77,070, dated April 21, 1868.

IMPROVED APPARATUS FOR DISTILLING PETROLEUM.

The Schedule referred to in these Letters Patent and making part of the same.

TO ALL WHOM IT MAY CONCERN:

Be it known that I, JAMES MILLER, of Allegheny City, in the county of Allegheny, and State of Pennsylvania, have invented a new and useful Improvement in Apparatus for Distillation of Petroleum; and I do hereby declare the following to be a full, clear, and exact description thereof, reference being had to the accompanying drawing, making a part of this specification, and to the letters of reference marked thereon, such drawing being a perspective view, partly in section, of my improved apparatus.

The nature of my invention consists in the construction of apparatus for distillation of petroleum, in which—
First. The crude oil is heated in a vacuum-still, the benzine driven off and condensed, and the oil is drawn off for further distillation in another still.

Second. A continuous distillation is effected in such subsequent still by the use of a vacuum, and with a small degree of heat, by feeding the oil while yet heated through a coil of pipe arranged in such still, and discharging it through small perforations into the still, at or near the bottom, whence it rises to the surface, and passes off in a vaporous form for condensation.

Third. The gases which pass through the condensing-apparatus into the receiving-tank are drawn off, and applied as fuel to heating the stills.

Fourth. By the use of gauge-cocks on the stills, and a section of glass in the pipes which discharge the condensed product into the receiving-tanks, the supply of oil into the still can be conveniently and easily regulated with reference to the rapidity of the distillation; and,

Fifth. The quality of the oil as it is run off may be tested from time to time, and if found too heavy to be profitably used for illuminating purposes, the heavy oil in the still may be drawn off separately, without stopping the distillation.

To enable others skilled in the art to make and use my invention, I will proceed to describe its construction and manner of use.

A is a still, of the ordinary form, having an aperture, A', properly closed when the still is in use, for the admission of oil; and a goose-neck, a, which connects with a condensing-pipe, a', the latter passing in a coil through water in the condensing-tank C. After leaving the tank C, it branches as at c c', one branch discharging into the benzine-tank D, and the other into the oil-tank E. The cocks e e' are attached for purposes yet to be explained.

The still A is filled to the usual depth with crude oil, heat is applied, the gasoline and benzine, with such other lighter products of distillation as it may be deemed desirable to drive off, are vaporized, passed through the condensing-coil a', condensed, and, the cock e being open and the cock e' closed, they are discharged into the benzine-tank D. In the pipe a', after it leaves the condensing-tank C, I insert a section of glass pipe, g, and attach a cock, f. The former enables one to observe the rapidity with which the distilling-process is being carried on, and by the latter I draw off, from time to time, portions of the distilled product, in order to test its gravity. As soon as the benzine is all driven over, I draw off, through a pipe, h, in the lower part of the still A, the oil thus freed of its lighter products, into a tank, F, refill the still, A, and continue the process as before.

B (shown partly in section) is a similar still, having a goose-neck, b, condensing-worm b', which also passes through water in the condensing-tank C, and after leaving it, discharges, by the branches i i', into the tanks D and E, as before. The cocks o o' perform a similar function to those shown at e e'. A glass section, g', is also inserted in the pipe b', and a test-cock, f', is attached thereto. From the tank F, a feed-pipe, h', carries the oil therefrom, by the aid of a pump, injector, or in any other convenient way, and discharges it into the feed-pipe m, which, passing into the still B, is coiled, or passes back and forth, as at m'. The lower pipe of such coil has a series of small apertures, n, through which the oil, fed in as described, passes out into the still, B. When the still is sufficiently full, heat is applied, as presently to be described, and vapors are driven off, which, passing through the condensing-worm b', are condensed, and (the cocks o o' being properly set) the condensed oil is discharged into the oil-tank E. By the use of a glass section of pipe, g', I am enabled to watch the rapid-

ity with which the distillation is being carried on, and by drawing off portions of the product from time to time by the cock f' , I am enabled to test the gravity. If at any time I find the product is too light, I set the cocks $o\ o'$ so as to discharge it into the benzine-tank D. If, on the contrary, the oil produced be too heavy to be profitably used for illuminating purposes, I increase the feed from the tank F through the pipe m , draw off a portion or all the heavy or residual oils in the still, B, by a cock, S, and so regulate the product without at all arresting the process.

In order to facilitate the vaporization of the oil in both stills, and avoid the necessity of preserving so high a temperature as is ordinarily required, I remove all atmospheric or other pressure, before commencing the work of distillation, by an air-pump attached to the pipe x , which, by its branches $x' x''$, is connected with the tanks D and E respectively, such branches being fitted with cocks $y\ y'$. To this end, the cocks $e\ e'$ or $o\ o'$, on the pipe leading to either still, A or B, should be opened, a partial or perfect vacuum effected, when the oil will vaporize at a much lower temperature than otherwise, and consequently a much less degree of heat will be required under the stills, and the danger from explosion, fire, &c., will be proportionately reduced.

It will be observed that the oil in the tank F has been already heated in the still, A; that it passes through a worm or coil, m' , which is imersed in a heated body of oil; that the oil is discharged therefrom in minute streams through the apertures n , in that part of the still, B, where the heat is the greatest; that it then runs through a body of heated oil, and, on reaching the surface of the oil in the still, is subject to no atmospheric or other pressure, and consequently, that all things being thus favorable to its vaporization, it will be distilled with great rapidity. I attach to the front of the still, B, and connecting therewith, a gauge-pipe, n' , and gauge-cocks n'' . By these I am enabled to ascertain at any time the amount of oil in the still, B.

If the oil in the tank F becomes cold before being run into the still, B, I reheat it by passing steam through a coil of pipe placed therein.

In the distillation of petroleum, it has been found that fixed gases, uncondensable in water, often pass over with the oily vapors, and of course are collected in the receiving-tank. These gases are a great source of danger, since they are combustible, and, when mixed with air, highly explosive. In order to remove them as an element of danger, and utilize them, I pump them out of the tanks D and E by an air-pump, attached to the pipe x , and force them through perforated pipes, l' , arranged in or around the furnace z , or if not needed for use as fuel, I pass them off through a pipe, opening at a considerable distance from the furnace, so as to avoid as perfectly as possible such elements of danger.

By a pipe, l , fitted with cocks $u\ u'$, I pump out the contents of either tank from time to time, without interrupting the distilling-process, which goes on continuously, as already stated.

In carrying on the process described, I do not limit myself to any particular number of stills, but, generally, I find that such stills, arranged in sets of two, are best for carrying on the distillation to advantage.

What I claim as my invention, and desire to secure by Letters Patent, is—

1. The combination of two or more vacuum-stills, one, A, for heating the oil, and driving off its more volatile ingredients, and the other, B, for carrying on a continuous distillation, by feeding therein the heated oil from still, A, through a coiled or zigzag pipe, m' , with apertures n , substantially as and for the purposes hereinbefore set forth.
2. The use, in the discharging-end of the condensing-pipe of oil-distilling apparatus, of a glass section, $g\ g'$, and cock f or f' , in connection with a vacuum-still, for ascertaining the rapidity of the condensation and the quality of the product, substantially as above set forth.
3. A coiled or zigzag pipe, m' , with perforations n , arranged in a vacuum-still, B, with a continuous feed, either separately or in combination with gauge-cocks n'' , constructed and used substantially as and for the purposes hereinbefore set forth.
4. Utilizing the uncondensed gases and vapors which are passed over in the process of distillation, by feeding them from the receiving-tanks, through perforated pipes l' , into the furnace, substantially as hereinbefore set forth.

In testimony whereof, I, the said JAMES MILLER, have hereunto set my hand:

JAMES MILLER.
